INVENTOR

By Harry D. Hildebrand
and Dennis D. Wileath

UNITED STATES PATENT OFFICE.

HARRY D. HILDEBRAND, OF MOUNT VERNON, OHIO.

METHOD OF EXCHANGING HEAT.

1,340,267.

Specification of Letters Patent. Patented May 18, 1920.

Original application filed January 2, 1917, Serial No. 140,093. Divided and this application filed April 21, 1919. Serial No. 291,425.

To all whom it may concern:

Be it known that I, HARRY D. HILDEBRAND, residing at Mount Vernon, in the county of Knox and State of Ohio, a citizen 5 of the United States, have invented or discovered certain new and useful Improvements in Methods of Exchanging Heat, of which improvements the following is specification.

10 In many of the arts, fluids, after being treated or after performing some function or purpose, are in a highly heated condition and it is desirable to utilize the heat contained in such discharged fluid in raising the temperature of another quantity of fluid. This exchange of heat is effected by causing the two fluids to flow along opposite sides of a conducting diaphragm, which will receive heat from one of the fluids and transmit it to the 15 other. While not always necessary or desirable, it is usual to cause the two fluids to flow in opposite directions, the fluid to be heated entering the exchange system at or adjacent to the point of discharge of the other fluid 20 from such system. While several conditions 25 may affect the efficiency of a heat exchanger, the main condition is the relation of the areas of the surfaces of the fluids in contact with the transmitting diaphragm to the quantity 30 of fluid flowing on opposite sides of the diaphragm at a given time, hence the greater the areas of the surfaces of the fluids in contact with the diaphragm, relative to the 35 quantities of the fluids, the greater the velocity of heat exchange which may be imparted to the fluids through the exchanger.

The invention described herein has for its object the method of effecting an exchange of heat between two fluids by causing them 40 to flow in their annular streams along opposite sides of a plurality of diaphragms formed of metal or other good conducting material, the respective fluids being caused to flow in progressively larger and smaller 45 annular streams. It is a further object of the invention to prevent material loss of heat through radiation by causing the respective streams to alternate one with the other in such manner that the more highly 50 heated fluid will flow between the annular streams of the cooler fluid. The invention is hereinafter more fully described and claimed.

In the accompanying drawings forming a 55 part of this specification, Figure 1 is a side

elevation of my improved heat exchanger; Fig. 2 is an end view of the same, and Fig. 3 is a transverse section of one of the elements of the exchanger.

While other forms of apparatus may be employed in the practice of the method described and claimed herein, it is preferred to employ the construction described and claimed in an application filed January 2nd, 1917, Serial Number 140,093, this application being a division thereof. As shown and described in said application, the preferred apparatus consists of two elements A and B which are formed by two series of pipes as a, b, c, etc., and 1, 2, 3, etc., of successively larger diameters, arranged one within the other, each succeeding outer section being made sufficiently shorter than the adjacent inner section to permit of connecting each section of one element with a corresponding section of the other element of the exchanger. Each succeeding section is hermetically secured to the inner adjacent section at its ends by any suitable means, preferably by welding. As hereinbefore stated, two elements constructed as above stated, 60 form a part of the heat-exchanger and are connected together by transversely arranged pipes 11, as clearly shown in Figs. 1 and 2. One of the fluids, preferably the hot fluid, enters at one end of the inner pipe, as a, of one element, as B, said pipe having its opposite end closed but connected to the second pipe as b of the other element A. This pipe b has its opposite end connected to the end 65 of the pipe c of the element B. In like manner, the alternate pipes c, e and g of the element B are connected to one end of pipes d, f and h of the element A, and the opposite ends of these letter pipes d, f and g are connected to pipes e, g and i of element B, 70 which has an outlet k for the cooled fluid. 75

The fluid to be cooled enters through the inlet 12 of the pipe 1 which is the outermost pipe in series A and flows through a connecting pipe into pipe 2 of element B, the opposite end of the pipe 2 is connected to the pipe 3 of element A, which in turn is connected to pipe 4 of element B. In like manner the alternate pipes 6, 8, of element B have one 80 end connected to pipes 7 and 9 of element A, and the opposite end of pipe 7 is connected to pipe 8 of element B, and the right hand end of pipe 9 of the element A in the diaphragm outlet for the oil which has been 85 90 95 100 105 110

heated in passing through the system. In practice it is preferred that the apparatus employed in the practice of the method should be so constructed that due regard 5 be had to frictional resistance, the several streams of fluids being as thin as possible.

It is characteristic of the operation of this improved system that the highly heated oil will pass through alternate pipes of each 10 element and be discharged from the outer pipe of one element, while the oil to be heated enters the outer pipe of one of the elements and flows through pipes alternating with those through which the hot fluids pass 15 and is finally discharged from one end of the inner pipe of one of the elements. It will be observed that as the cold fluid enters pipe 1, through inlet 12, it is outside of the pipe *h*, through which passes the comparatively 20 cooled fluid and the fluid to be heated passes to the pipe 2, which is surrounded by the pipe 1, which forms the last pass of the fluid to be cooled and has the outlet *h* for the discharge of the cooled fluid. As fluid to be 25 heated flows along the several pipe sections, it is gradually raised in temperature and the next to the last pass of the fluid to be heated is through the pipe 6, which is immediately outside of the pipe *a*, through which the hot 30 fluid first passes.

While in most cases the method will be so practised that the fluid from which the heat is to be extracted flows outwardly in successive steps, while the fluid to be heated 35 moves inwardly in a similar manner, the flows or movements of the fluids may be reversed without departing from the spirit of the invention.

It will be understood that an element may consist of any desired number of sections but 40 care should be taken to employ so many sections that there will not be so great a difference of temperature between the inner pipe section and the outer pipe section that rupture will result from differences of elongation 45 due to differences of expansion of the successive sections.

It is characteristic of the preferred practice that the streams in their coolest condition or state are outermost and hence there 50 will be little loss of heat from radiation from the hotter innermost stream.

No claim is made herein to an apparatus employed for the practice of the method, the preferred form of apparatus for the practice 55 of the method being described and claimed in an application filed January 2, 1917, Serial Number 140,093.

I claim herein as my invention:

1. The method of effecting an exchange of 60 heat between fluids, which consists in causing the fluids to be cooled to flow in progressively larger annular streams, and the fluid to be heated to flow in progressively smaller annular streams, which alternate with the 65 streams of the fluid to be cooled.

2. The method of effecting an exchange of heat between fluids which consists in causing a fluid of one temperature to flow in progressively larger annular streams and a fluid of 70 another temperature to flow in progressively smaller annular streams which alternate with the streams of the first fluid.

In testimony whereof I have hereunto set my hand.

HARRY D. HILDEBRAND.
